GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

HYDROCARBON OIL CONVERSION

Application filed December 7, 1925. Serial No. 73,592.

This invention relates to improvements in the art of hydrocarbon oil conversion, and refers more particularly to subjecting hydrocarbon oil to the action of heat and super-atmospheric pressure for the purpose of producing substantial yields of commercial products therefrom, and more specifically directed to the production of gasoline-like bodies.

10 The present invention, in brief, comprises subjecting raw oil to the action of heat at a predetermined superatmospheric pressure in order to separate said raw oil into vapors (both distillate and reflux) and unvaporized residue.

The invention further contemplates cracking said reflux separately in the same system, and also contemplates the cracking of said residuum separately in the same system, all 20 as part of a continuous process.

Many other objects and advantages will be immediately apparent from the following description.

The single figure in the drawing is a dia- 25 grammatic side elevational view, partly in vertical section, of my apparatus.

In the drawing, the raw charging stock from any suitable source of supply is introduced through the inlet line 1, controlled by 30 valve 2, and forced by means of the pump 3 into a continuous elongated heating tube 4 mounted in the furnace 5, where it is heated to a conversion temperature, as will be hereinafter more particularly explained. This 35 heated charging stock passes through the transfer line 6, controlled by valve 7, discharging into the enlarged expansion chamber 8, which may be placed in a vertical or horizontal plane, as desired, and which may 40 or may not be externally heated, as desired. The expansion chamber 8 may be insulated to prevent the radiation of heat.

The heated oil introduced through the line 6 into the chamber 8 will partially vaporize, 45 and the separated vapors will be removed through the vapor line 9, in which is interposed the valve 10. The vapor line 9 may introduce the vapors into the dephlegmator 11, where they travel upwardly, being retarded by the baffles or bubble plates 12.

These vapors, in their upward travel, may be cooled by contact with any suitable cooling medium which may be introduced thereto, such as a part of the raw oil which may be introduced through the inlet line 13', controlled by valve 14', and in which is interposed a pump 15'. 55

The uncondensed vapors, after passing through the dephlegmator 11, may be withdrawn through the line 13, in which is interposed the throttle valve 14, and cooled and condensed in the condenser coil 15 set in condenser box 16. These condenser vapors may pass through the line 17, controlled by valve 18 and collected in receiver 19. This 60 receiver may be provided with the incondensable gas relief pipe 20, controlled by valve 21, and with the liquid draw-off 22, controlled by valve 23. It is, of course, understood that a portion of the liquid collected in the receiver 19 may be diverted and returned to the dephlegmator, if found desirable to control the temperature therein, or for the production of a product of a desired end boiling point. The liquid reflux 65 condensate collecting in the dephlegmator 11 may be drained into the reflux line 24, in which is interposed the valve 25, and may be diverted, either in part or totally, through the line 26, in which is interposed the valve 70 75 27, it being understood, of course, that as a preferred form of operation, the major portion of the reflux condensate will be always returned, as will be now explained, instead of being diverted through the pipe 26. 80 85

The reflux condensate which is not diverted through the pipe 26 continues to flow through a continuation 24' of the pipe 24, controlled by valve 25', passing through the elongated heating tube 28 mounted in the furnace 5. A reflux pump 29 may be interposed in the return line 24' for the purpose of mechanically imposing a higher pressure on the reflux being returned to the heating 90 95 tube 28. In some cases it may be desirable to by-pass the pump, in which event the valves 30 are closed and the valve 31 opened.

The reflux from the heating tube 28 passes by means of the transfer line 32, in which is 100

interposed the throttle valve 33, being introduced into the chamber 8.

The unvaporized residue from the chamber 8 may be withdrawn and may or may not be diverted through the line 34, controlled by the valve 35. In one of the preferred forms of the invention, the unvaporized residue is returned by means of the line 36, controlled by valve 37, to the heating tube 38, also mounted in the furnace 5. A pump 39 is interposed in the residue return line 36 for the purpose of mechanically imposing a higher pressure upon said residue as it is being returned to the heating tube 38. After passage through the heating tube 38, the residue may pass, by means of the transfer line 40, controlled by valve 41, into the expansion chamber 8.

The furnace 5 is preferably of the side fired type, fired by means of the burners 42, which furnace is divided into the combustion chamber 43 and tube chamber 44 by means of the partition wall 45, the course of travel of the gases of combustion being designated by the arrow. It is, of course, understood that the drawing is merely diagrammatic, and that the heating tubes 4, 28 and 38 may be mounted in separate furnaces; also that the design of the furnace itself may be changed without departing from the scope of the invention.

The process and apparatus of the present invention are extremely flexible in operation, as will be hereinafter more particularly brought out.

The essence of the present invention resides in the idea of subjecting the returned reflux condensate to the highest temperature, the raw oil to a temperature somewhat lower, which may, for instance, be referred to as an intermediate temperature, and the returned unvaporized residue to a still lower or lowest temperature. It is known that reflux condensate requires a much higher temperature for efficient conversion than the raw charging stock and the unvaporized residue. The present invention combines in a single system a process and apparatus so designed that the reflux is subjected to the highest temperature, the raw oil to an intermediate temperature, and the residue to a lower temperature, all of said temperatures being so regulated and controlled as to operate under the most efficient conditions. Thus, each division is subjected to its most efficient temperature without overheating or underheating the constituents which make up the composite body. The regulation of temperature is for the purpose of converting relatively narrow boiling point fractions of oils so as to bring about maximum conversion at a lower average temperature than would prevail if the three oils were blended together for an equivalent percentage of gasoline formation.

As a further feature of the invention, these

three different types of oil are introduced into the same expansion chamber.

As a further feature of the invention, a higher pressure may be maintained on the reflux, and intermediate pressure maintained on the raw oil, and the lowest pressure maintained on the residue. It will thus be seen that the reflux, being introduced to the expansion chamber 8, will be materially reduced in pressure and, due to its high heat, will yield a maximum amount of vapors which are withdrawn through the vapor line 9. A substantial amount of vaporization of the raw oil will also take place when it is introduced to the chamber 8 due to the reduction in pressure and the temperature to which it has been subjected.

It is, of course, understood that in some instances it will be desirable to maintain any two or three of the heating tubes 4, 28 and 38 at substantially the same pressure. Further, the entire system may be maintained under a uniform pressure, or differential pressures employed by manipulation of the valves and pumps shown.

The reflux may be cracked at that temperature and pressure at which it will be in the vapor phase, and the raw oil and residue may be cracked in the liquid-vapor phase or be heated at that temperature and pressure, where the oil is all or substantially all in liquid condition. The expansion chamber 8 may be maintained at the same pressure as the lowest pressure existing in any of the three tubes 4, 28 and 38, or it may be operated at a lower pressure than that prevailing in the tubes.

An illustrative run of this process may be cited as follows: the raw charging stock introduced through the line 1 may be heated to a temperature of, say 870° F. more or less and a pressure maintained thereon of, say, 300 pounds more or less in the tube 4. The raw oil heated to this temperature, upon being introduced to the expansion chamber 8 will separate into a maximum quantity of vapors to be withdrawn through the pipe 9. The unvaporized residue may be withdrawn through the line 36, the valve 37 being opened and the valve 35 closed, and returned by means of the residue pump to the heating tube 38 where it may be subjected to a temperature of, say, 800° F. more or less and maintained under a pressure of, say, 250 pounds more or less. This residue is introduced to the expansion chamber 8 through the line 40 and will separate in the reaction chamber into vapors and unvaporized residue. The reaction chamber 8 may be maintained under pressure similar to the pressure maintained in the heating tube 38, namely 250 pounds, or it may be maintained under a lower pressure by manipulation of the valve 10. The reflux condensate collecting in the dephlegmator 11 may be returned through

the line 24' and passed through the heating tube 28, where it is subjected to a temperature of, say, 1100° F. more or less and maintained under a pressure of, say, 400 pounds more or less. This reflux is discharged through the line 32 into the expansion chamber 8 where, due to its sudden reduction from a pressure of, say 400 pounds more or less to a pressure of 250 pounds more or less, maintained in 10 the chamber 8, it separates instantly into vapors and a small portion of unvaporized product.

By the present invention, it is obvious that I secure the beneficial results of combining 15 the vapors from the reflux, raw oil and residue in the expansion chamber 8. It is also obvious that one of the advantages of the present invention is that the oil being subjected to the highest temperature will not 20 precipitate a substantial amount of carbon in the tubes, and further, due to the separate heating, as described, the unvaporized residue which does precipitate substantial amounts of carbon is subjected to the lowest 25 temperature.

It is, of course, understood that the figures used in the illustrative run are by no means arbitrary, and that these figures may be varied as determined by conditions of opera- 30 tion.

I claim as my invention:

1. A process of hydrocarbon oil conversion, comprising subjecting charging stock to the action of heat and superatmospheric pressure 35 to produce substantial vaporization, separating the vaporized portions from the unvaporized portions, subjecting the vaporized portions to reflux condensation, returning the reflux condensate and subjecting it to a higher 40 temperature than that to which the charging stock is subjected, in returning the unvaporized residue and subjecting it to a lower temperature than that to which the charging stock is subjected, and in introducing the 45 heated charging stock, reflux condensate and residue into a common expansion zone.

2. A process of hydrocarbon oil conversion, comprising subjecting charging stock to the action of heat and superatmospheric pressure 50 sure to produce substantial vaporization, separating the vaporized portions from the unvaporized portions, subjecting the vaporized portions to reflux condensation, returning the reflux condensate and subjecting it to a 55 higher temperature than that to which the charging stock is subjected, in returning the unvaporized residue and subjecting it to a lower temperature than that to which the charging stock is subjected, and in introducing the 60 heated charging stock, reflux condensate and residue into a common expansion zone, maintaining differential pressures on the reflux condensate, charging stock and unvaporized residue while being subjected to 65 said higher and lower temperatures.

3. A process of hydrocarbon oil conversion, comprising subjecting charging stock to the action of heat and superatmospheric pressure to produce substantial vaporization, separating the vaporized portions from the 70 unvaporized portions, subjecting the vaporized portions to reflux condensation, returning the reflux condensate and subjecting it to a higher temperature than that to which the charging stock is subjected, in returning 75 the unvaporized residue and subjecting it to a lower temperature than that to which the charging stock is subjected, and in introducing the heated charging stock, reflux condensate and residue into a common expansion 80 zone, maintaining said reflux condensate while being subjected to said higher temperature under a higher superatmospheric pressure than is maintained on the charging stock and residue.

4. A process of hydrocarbon oil conversion, comprising subjecting charging stock to the action of heat and superatmospheric pressure to produce substantial vaporization, separating the vaporized portions from the 90 unvaporized portions, subjecting the vaporized portions to reflux condensation, returning the reflux condensate and subjecting it to a higher temperature than that to which the charging stock is subjected, in returning the 95 unvaporized residue and subjecting it to a lower temperature than that to which the charging stock is subjected, and in introducing the heated charging stock, reflux condensate and residue into a common expansion 100 zone, maintaining said reflux condensate and said charging stock at a higher superatmospheric pressure while being subjected to heat than is maintained on the unvaporized residue.

5. An apparatus for hydrocarbon oil conversion, in combination with separate charging stock, reflux and unvaporized residue heating tubes mounted in a heating zone, of an expansion chamber communicating with 110 said separate heating tubes, of a vapor draw-off from said expansion chamber, a dephlegmating means communicating with said latter vapor draw-off, means communicating between the dephlegmating means and the reflux heating tube, and means communicating between the expansion chamber and the unvaporized residue heating tube.

6. An apparatus for hydrocarbon oil conversion, in combination with separate charging stock, reflux and unvaporized residue heating tubes mounted in a heating zone, of an expansion chamber communicating with 120 said separate heating tubes, of a vapor draw-off from said expansion chamber, a dephlegmating means communicating with said latter vapor draw-off, means communicating between the dephlegmating means and the reflux heating tube, means communicating between the expansion chamber and the unvap- 125

orized residue heating tube, and means for maintaining differential pressures on the above elements.

7. A hydrocarbon oil cracking process
5 which comprises heating charging oil to cracking temperature under pressure, separating the vapors from the unvaporized oil, dephlegmating the vapors thereby forming reflux condensate, separately heating the reflux condensate and the unvaporized oil to cracking temperature, the reflux condensate being heated to higher temperature than the charging oil and the unvaporized oil being heated to lower temperature than the charging oil, combining the vapors released from the charging oil, reflux condensate and unvaporized oil, and condensing the commingled vapors.

8. A hydrocarbon oil cracking process
20 which comprises heating charging oil to cracking temperature under pressure, separating the vapors from the unvaporized oil, dephlegmating the vapors, thereby forming reflux condensate, separately heating the reflux condensate to a vapor phase cracking temperature in excess of the temperature to which the charging oil is heated, separately heating the unvaporized oil to a cracking temperature lower than that to which the
25 charging oil is subjected, combining the vapors of the cracked reflux condensate with the vapors evolved from the unvaporized oil, and condensing the commingled vapors.
